US00D886850S

(12) **United States Design Patent** (10) Patent No.: **US D886,850 S**
 Kim et al. (45) Date of Patent: ** Jun. 9, 2020

(54) **DISPLAY SCREEN OR PORTION THEREOF WITH GRAPHICAL USER INTERFACE**

- (71) Applicant: **Samsung Electronics Co., Ltd.**, Suwon-si (KR)
- (72) Inventors: **Daewon Kim**, Seoul (KR); **Hyun Yeul Lee**, Seoul (KR); **Insheik Martin Jung**, Seattle, WA (US); **Hyosang Bang**, Seoul (KR); **Youngseong Kim**, Seoul (KR); **Jaewon Park**, Seoul (KR); **Jiyoung Han**, Seoul (KR)
- (73) Assignee: **SAMSUNG ELECTRONICS CO., LTD.**, Suwon-si (KR)
- (**) Term: **15 Years**
- (21) Appl. No.: **29/654,449**
- (22) Filed: **Jun. 25, 2018**

Related U.S. Application Data

- (63) Continuation of application No. 29/612,136, filed on Jul. 28, 2017, now Pat. No. Des. 821,435.

Foreign Application Priority Data

CLAIM

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of a display screen or portion thereof with graphical user interface showing our new design according to a second embodiment;

FIG. 3 is a front view of a display screen or portion thereof with graphical user interface showing our new design according to a third embodiment;

FIG. 4 is a front view of a display screen or portion thereof with graphical user interface showing our new design according to a fourth embodiment; and,

FIG. 5 is a front view of a display screen or portion thereof with graphical user interface showing our new design according to a fifth embodiment.

The outermost broken lines illustrate a display screen or portion thereof and form no part of the claimed design. The remaining broken lines in the drawings illustrate portions of the graphical user interface that form no part of the claimed design.

1 Claim, 5 Drawing Sheets
